SHOE STRETCHER

Filed Oct. 12, 1929

11 12 INVENTOR
James Smart

ATTORNEY.

UNITED STATES PATENT OFFICE

JAMES SMART, OF ORLANDO, FLORIDA

SHOE STRETCHER

Application filed October 12, 1929. Serial No. 399,292.

The object of the invention is to provide a simple, strong and effective device capable, after insertion in the shoe, of effectively stretching the shoe laterally as well as raising the top; to provide a construction where-
 5 in the lateral stretching may be effected without raising the top; to provide adjustable means for the top raising element, so that the definite movement of the latter may at-
 tend the movement of the elements effecting
 10 the lateral stretching; and to provide a construction wherein the parts may be readily disassembled without the necessity for tools for so doing.

With this object in view, the invention con-
 15 sists in a construction and combination of
 parts of which a preferred embodiment is
 illustrated in the accompanying drawings,
 in which:

20 Figure 1 is a perspective view of the in-
 vention.

Figure 2 is a top plan view with the top
 lifting element swung to one side.

Figures 3, 4 and 5 are respectively sectional
 25 views on the planes indicated by the lines
 3—3, 4—4 and 5—5 of Figure 1.

The body of the stretcher simulates a last
 and comprises the two side sections 10 hinged-
 30 ly connected at the rear end, as indicated at
 11, a guide opening being prepared in the rear
 end of the body element, half in one section
 and half in the other, for the passage of the
 shank of the wedge operating screw 12, the
 latter being provided with a transverse han-
 35 dle 14 to permit it being turned.

The screw 12 is threadingly engaged with
 the globular nut 15 seated in hemispherical
 depressions formed in the inner faces of the
 two side elements 10, this nut being provided
 40 with diametrically disposed trunnions 16
 journaled in the side members. At the for-
 ward end, the screw 12 has a swivel connec-
 tion 17 with a spreader wedge 18, the latter
 traversing lateral recesses 19 in the side mem-
 45 bers and these recesses on the bottom walls
 being undercut, as indicated at 20, for the
 reception of pendent ribs 21 on the bottom of
 the wedge.

In the operation of the feed screw, the nut
 50 being held by engagement in the hemispheri-

cal recesses and by its trunnions, the wedge
 is moved relative to the body member and
 if the direction be toward the toe, the side
 edges of the wedge effects spreading action
 of the lateral or side members. The reverse
 55 movement of the screw serves to move the
 wedge in the other direction and the pendent
 ribs engaging the undercut portions of the
 recesses, serves to draw the side members
 toward each other. Thus the body of the
 60 spreader as a whole is expanded laterally,
 after insertion in the shoe, by the movement
 of the wedge to effect the lateral stretching
 of the shoe and is easily withdrawn, after
 performing the stretching operation, by re-
 65 versing the movement of the wedge through
 the turning of the operating screw in the op-
 posite direction, thus making easy withdraw-
 al from the shoe possible.

To provide for lifting the top of the shoe,
 a stretcher plate 22 is provided, this stretcher
 plate being pivotally connected with the
 globular nut 15, as indicated at 23. It spans
 the two side elements of the body and on the
 under face is provided with a rib 24 travers-
 70 ing a slot 25 in the body formed half in one
 side element and half in the other. The
 wedge, near the nose, is provided with an ad-
 justing screw 26 having a globular head en-
 gaging the under face of the stretcher plate.
 75 As the wedge is advanced toward the toe of
 the body portion, the head of the screw 26,
 moving in a plane at an acute angle to the
 plane of the top of the body portion, gradu-
 ally rises above the top of the body por-
 80 tion and, bearing on the under face of the
 stretcher plate, raises the latter to lift and
 stretch the top of the shoe. The screw, by
 virtue of its threads, may be raised and
 lowered in the wedge to determine the time
 85 of initial engagement with the stretcher
 plate and thus determine a specified stretch-
 ing operation of the latter.

The stretcher plate being pivotally mount-
 ed on the body portion, when it is desired not
 to lift the top of the shoe in the stretching
 operation, the plate may be swung laterally
 to one side and the body portion inserted and
 the side elements actuated to effect the later-
 al stretching operation solely.

The parts of the device may be easily disassembled by advancing the spreader wedge toward the toe until the pendent ribs are disengaged from the undercut recesses of the side slots. Then the two side elements of the body may be swung apart on their hinge connection which will permit the nut, the screw and the wedge to be lifted out. Thus the parts may be easily reached for cleaning and for replacement when necessary.

10 The invention having been described, what is claimed as new and useful is:

1. A shoe stretcher comprising a body consisting of pivotally connected side elements, a spreader wedge enclosed by the same, a nut seated jointly in said elements, a wedge actuating screw threadingly engaged with the nut and having a swivel connection with the wedge, and a spreader plate spanning the two side members of the body, the wedge being provided with an adjustable member having a slide bearing with the under surface of said stretcher plate.
2. A shoe stretcher comprising a body consisting of pivotally connected side elements, a spreader wedge enclosed by the same, a nut seated jointly in said elements, a wedge actuating screw threadingly engaged with the nut and having a swivel connection with the wedge, and a spreader plate spanning the two side members of the body, the wedge being provided with an adjusting screw formed with a globular head having a sliding engagement with the under face of said stretcher plate.

35 In testimony whereof he affixes his signature.

JAMES SMART.
